UNITED STATES PATENT OFFICE.

SAMUEL T. WHITE, OF DAVENPORT, IOWA.

CLOTHES-WRINGER.

1,148,133.

Specification of Letters Patent. Patented July 27, 1915.

Application filed June 3, 1915. Serial No. 31,947.

To all whom it may concern:

Be it known that I, SAMUEL T. WHITE, a citizen of the United States, residing at Davenport, in the county of Scott and State 5 of Iowa, have invented new and useful Improvements in Clothes-Wringers, of which the following is a full, clear, and exact description.

My invention relates to domestic clothes 10 wringers, particularly such as are used in connection with wash-tubs and washing machines.

The object of my invention is to prevent 15 injury to the hands of the operator when feeding clothes to and between the rubber rollers of a clothes wringer by providing a guard or fender with which the fingers come in contact during the insertion of the clothes before coming in contact with the roller, 20 and thus warn the operator of the dangerous proximity of his fingers to the same, and constructing said guards so that they will not prevent free access to said roller whenever it is deemed necessary. This I accomplish by the means hereinafter fully described, and as particularly pointed out in 25 the claims.

In the drawings: Figure 1 is a front elevation of a clothes wringer having my improvements applied thereto. Fig. 2 is a 30 vertical section thereof taken on dotted line 2—2, Fig. 1. Fig. 3 is a side view of a fragment of said clothes wringer embodying a modification of my invention. Fig. 4 is a 35 horizontal section thereof taken on dotted line 4—4, Fig. 3. Fig. 5 is a vertical section of the same taken on dotted line 5—5, Fig. 3, looking in the direction indicated by the arrows. Fig. 6 is a transverse section 40 of a modified form of journal or trunnion of one of said guard rollers.

The principal features of construction of the clothes-wringer to which my improvements are applied may be as shown in the 45 accompanying drawings, or may conform to any of the other well known types of clothes-wringers now in extensive use. The clothes-wringer shown in the drawings comprises side-frames A, A, which curve upward from 50 the screw-plates *a* that attach the wringer to the top of a washing-machine or to any other suitable support. The upper portions of these side-frames are provided with stationary bearings for the journals of the 55 lower roller B, and are provided with outwardly projecting arms *b* which, near their

extremities, have sockets into which the depending fulcrumal pins *c* on the adjacent ends of the supporting jaws C enter. These jaws are horizontally disposed members 60 that extend rearwardly to about the vertical plane of the rear vertical edges of side-frames A and at points immediately over the journals of the lower roller are provided with suitable inverted open bearings for the 65 journals of the upper roller D. The upper roller is kept in engagement with the lower roller B and is made to press down upon the same by means of coil-springs *d*, *d*, that surround posts *e*, *e*, whose lower ends are 70 secured in the upper edges of frames A and extend through suitable openings in jaws C and have their upper ends screw-threaded and engaged by thumb-nuts E, which latter screw down upon the ends of a bridge F 75 and regulate the pressure of the springs upon said jaws.

My invention comprises two pairs of small guard-rollers, 2 and 3, which are, preferably, about one-half the diameter of the 80 wringer-rollers, and are, preferably, made of wood. The lower guard rollers 3, 3, of each pair are arranged parallel to and along each side of the lower wringer roller B, and their journals rest and revolve in permanent 85 bearings, and the upper guard-rollers 2, 2, of each pair are arranged parallel to and along each side of the upper wringer roller D and have their journals 4 in vertically elongated bearings 5, 5. The bearings for 90 these guard rollers are made in corresponding wings 6, 6, projecting laterally from the sides of vertically disposed supporting-plates 7, 7, which latter are interposed between the ends of the wringer-rollers B and 95 D and the bearings therefor in the side-frames and the jaws of the wringer. These supporting-plates are flat and have vertical slots 8, 8, that extend upward from the lower edge thereof to a point above the 100 journals of the lower roller and extend down from the upper edge thereof to a point below the plane of the journals of the upper roller D, and are wide enough to permit said journals to pass loosely there-through. If desired, the side edges of plates 105 7, 7, may be flanged toward the center of length of the wringer roller, and wings 6, 6, may project laterally from said flanges. While, however, this construction is preferred, it is not essential.

The relative position of the guard-rollers

on each side of the wringer-rollers is such that they are separated sufficiently to permit the insertion of the clothes between the wringer rollers in the usual manner, but 5 when the fingers of the hand come in contact with the guard-rollers the operator will know at once that he is running the risk of getting his fingers pinched and can withdraw his hand. If he thinks it is safe and 10 practicable, however, he can shove his fingers closer to the wringer rollers and thereby force the upper guard-roller to move upward in its vertically elongated bearing out of the way. Should it, at any time, be 15 desired to move the hand into contact with the wringer-rollers the upper guard roller can be moved to the upper limits of its vertically elongated bearings and then dropped into the offsets 9, 9, extending 20 downwardly and outwardly from the upper ends thereof, in which said journals may be retained and maintain said upper roller in an elevated position until it is desired to move it back to its vertical bearings and 25 allowed to drop down into the lower ends thereof.

In Figs. 3, 4 and 5, I show a modified construction of the bearings for the guard-rollers. In this modification the upper portion 30 of the wings are provided with vertically disposed tubular boxes 10, 10, the sides of which facing the center of length of the upper guard-roller, are provided with vertical slots 12, 12, for the passage there- 35 through of the journals 13, 13, of said upper roller. These journals extend into cylindrical blocks 14, which are normally kept at the lower limits of their vertically slid- 40 able movement in the bores of said boxes by means of coil expansion springs 15, 15, the downward pressure of which is regulated by the screws 16 tapped down into the upper ends of said bores. The only difference in 45 the use of this modified form of bearings for the journals of the upper guard-roller is that the downward pressure of said upper roller can be increased over that of the downward pressure of the upper guard-rollers shown in Figs. 1 and 2 of the draw- 50 ings, which latter depend entirely upon their weight to retain them in their lowermost positions.

While I much prefer to make the elements hereinbefore referred to as guard-rollers 55 revolute, yet it is apparent they could be easily converted into non-revolute elements, if desired, without departing from the spirit of my invention, simply by making their journals or trunnions square in cross-section, as shown in Fig. 6 of the drawings.

What I claim as new is:

1. In a clothes-wringer, the combination with the upper and lower rollers thereof, of a pair of guard-rollers whose axes are in 65 the same vertical plane, one of which has

stationary bearings and the other of which has vertically elongated bearings, and one of which is arranged alongside of and parallel to said lower roller and the other of which is arranged alongside of and parallel 70 to the said upper roller.

2. In a clothes-wringer, the combination with an upper and lower wringer-roller, and bearings therefor, of a supporting-plate interposed between the ends of said rollers 75 and their bearings, and an upper and lower guard-roller; said lower guard-roller being arranged alongside of and parallel to the lower wringer-roller and journaled in circular bearings in the laterally flaring por- 80 tion of said supporting-plate, and said upper guard-roller arranged alongside of and parallel to said upper wringer-roller and journaled in vertically elongated bearings 85 in said flaring portion of the supporting-plate above the bearings of the lower guard-roller.

3. In a clothes-wringer, the combination with an upper and lower wringer-roller, and bearings therefor, of a supporting-plate 90 interposed between the ends of said rollers and their bearings, and an upper and lower guard-roller; said lower guard-roller being arranged alongside of and parallel to the lower wringer-roller and journaled in circular bearings in the laterally flaring portion 95 of said supporting-plate, and said upper guard-roller arranged alongside of and parallel to said upper wringer-roller and journaled in vertically elongated bearings hav- 100 ing outwardly and downwardly extended offsets from their upper ends.

4. In a clothes-wringer, the combination with an upper and lower wringer-roller, and bearings therefor, of a supporting-plate 105 interposed between the ends of said rollers and their bearings and having vertical slots extending downward from the upper edges thereof and upward from the lower edges thereof for the passage of the journals of 110 said rollers, and an upper and lower guard-roller; said lower guard-roller being arranged alongside of and parallel to the lower wringer-roller and journaled in circular bearings in the laterally flaring por- 115 tion of said supporting-plate, and said upper guard-roller arranged alongside of and parallel to said upper wringer-roller and journaled in vertically elongated bearings in 120 said flaring portion of the supporting-plate above the bearings of the lower guard-roller.

5. In a clothes-wringer, the combination with upper and lower rollers, and bearings therefor, of a supporting-plate interposed between the ends of said rollers and their bearings and having lateral wings project- 125 ing from their vertical edges, of two pairs of guard-rollers the lower ones of which are journaled in circular bearings in the lower portions of said wings on each side of and 130

parallel to the lower wringer-roller, and the upper roller of each pair being journaled in vertically elongated bearings in said wings above said lower guard-roller.

- 5 6. In a clothes-wringer, the combination with an upper and lower wringer-roller, and bearings therefor, of a supporting-plate interposed between the ends of said rollers and their bearings, and having vertical slots 10 extending down from their upper edges, and vertical slots extending up from their lower edges through which the journals of said wringer-rollers pass, and said supporting-plate having lateral wings and two pairs of 15 guard-rollers the lower ones of which are journaled in circular bearings in the lower portions of said wings alongside of and parallel to the lower wringer-roller and the upper guard-rollers of each pair journaled

in vertically elongated bearings in said 20 wings alongside of and parallel to the upper wringer-rollers.

7. In a clothes-wringer, the combination with an upper and a lower wringer-roller, and bearings therefor, of supporting-plates 25 interposed between the ends of said rollers and their bearings, and a guard-roller arranged alongside of and parallel to said upper wringer-roller and journaled in vertically elongated bearings in the projecting 30 side portions of said supporting-plates.

In witness whereof I have hereunto set my hand this 26 day of May, 1915.

SAMUEL T. WHITE.
